UNITED STATES PATENT OFFICE.

CURTIS L. HOWSE, OF DETROIT, MICHIGAN, ASSIGNOR TO CRAIG DAMPER REGULATOR COMPANY, A CORPORATION OF DELAWARE.

HYDRAULIC ENGINE FOR CONTROL DEVICES.

Application filed March 2, 1922. Serial No. 540,652.

My invention has for its general object to provide a novel and improved engine, hydraulically operable to regulate the position of a part to be controlled by movement 5 of the engine-piston to, and its maintenance in, different positions longitudinally of its cylinder, which will be simple in construction, efficient, powerful and smooth in its functioning, highly sensitive to control of its 10 piston movement, rugged and durable in structure and readily adaptable to diversified utilization.

For attainment of these and other objects, which will become apparent to those skilled 15 in the art from the following description, taken in conjunction with the illustrated drawings, my invention consists in the combinations hereinafter set forth and the features of construction set forth and claimed.

20 In various situations it is desirable to regulate the position of a part of one apparatus accordantly with conditions that affect the position of the parts of a condition-responsive apparatus through the intermediary of an engine which is controlled by the condition-responsive part and which, actuated by power derived from some convenient source, forcefully actuates the part to be controlled. For one instance, it is desirable 25 to move the stack-damper of a steam boiler furnace in accordance with pressure conditions existing in the boiler of the furnace, and my invention may be embodied in form to actuate such a stack-damper accordantly with such pressure conditions as 30 the same are shown by the movements of a pressure-responsive device. In the drawing I illustrate my invention in such an embodiment, for purposes of disclosure of one practical 35 application thereof but without intent to limit the invention to such utilization.

In the drawing, Fig. 1 is a diagrammatic side elevation with parts broken away showing my invention applied to damper regulation accordantly with steam pressure conditions; Fig. 2 is an enlarged view with parts broken away; Fig. 3 is a small plan view of the parts shown in Fig. 2; and Fig. 4 is a detail of an adjustable crank arrangement.

In the drawing 10 represents the steam boiler of a furnace 11, the stack 12 of which contains damper 13 to be moved accordantly with variations in boiler pressure. The 55 damper regulating engine 14, valve-con-

nectible with a source of liquid pressure diagrammatically indicated at pump 15, has its piston connected to operate the damper and has its controlling valve operatively connected with a pressure-responsive device 16, 60 which communicates with the steam boiler and therefore constitutes one available form of condition-responsive device, the movements of which will valve-control the engine 65 operation.

Engine 14 comprises a piston 17 in a cylinder 18, the piston being loaded, as by weight 19 tending to raise it, so as to tend to move toward one end of the cylinder, and this end only of the cylinder is open, as at 70 the port 20, for reception or expulsion of liquid from the source 15. In the specific construction shown weight 19 is adjustable on a lever 21 which is pivoted as at 22 and which also carries the rack segment 23 for 75 operating a gear wheel 24 on the shaft of damper 13, the opposite end of said lever having link connection 25 with the piston rod 26 of the engine. The hydraulic pressure supply pipe 27 connects with the casing 80 of the valve structure 28, the pipe opening to the vertical cylinder 29 for a double-headed supply valve 30 at an elevation slightly above that of port 20 so that water pressure may constantly be exerted between the valve heads in any position of the limited range of axial movement of the valve. In lowered position the valve will 85 open communication between fluid supply pipe 27 and port 20; in mid-position or neutral position it will close the port 20, sealing the liquid-receptive end of the cylinder; and in raised position it opens communication from port 20 through the bottom of valve cylinder 29 to a relief connection 31 piped, say, to a water-disposal sewer, and preferably have a branch connection 32 to the lower end of the cylinder of the engine, so as to maintain the latter 90 normally under atmospheric pressure and to drain off any liquid that may leak into it. A duct 33 may also lead from this relief connection to the valve-cylinder above the valve, so that the valve will be perfectly 95 balanced.

The condition-responsive device 16 that primarily will control the movements of valve 30 may be of any suitable extensible type, such as bellows-diaphragm or spring-tube construction, and is herein shown as 100 105 110

- comprising a battery of Bourdon tubes 35 supported at one end on a suitable bracket 36 and at that end having common connection through a suitable header 37 with the steam pipe 37 opening to the boiler. The free end of the tubes may be provided with a union 38 to close them and to afford mechanical connection to the valve-controlling lever system, so that pressure-responsive movement of said head or union 38, in a generally vertical direction, accordantly with the expansion or contraction of the tubes under varying pressure, may conveniently be utilized.
- 15 The slide valve 30 is subjected to dual control from the pressure-responsive device on the one hand and the engine piston on the other, so that it may be moved from neutral position to connect port 20 with, alternatively, the source of pressure supply or the relief connection, by the condition-responsive device, and then may be moved back to neutral position by the piston as the result of the piston travel following from the introduction or expulsion of liquid due to the first-stated movement of the valve.
- In the specific construction shown the valve stem 30 is connected to horizontal lever 40 which has two pivotal connections 41 and 42 to links 43 and 44 for respective connection to the piston-controlled part and to the condition-responsive device 16, such lever 40 being preferably adjustably counterweighted as at 45 to load the pressure responsive part.
- 30 Link 44 may make direct pivotal connection as at 46 with the movable head 38 of the Bourdon spring, and for adjustment it may include a turnbuckle 47. Link 43 is pivoted as at 49 to an adjustable crank pin of a 35 rocking head 50, which is mounted in a suitable ear of the bracket 36 and has connected with it an operating lever 51, the slotted end 52 of which connects with a pin on the vertical bar 53 carried by and moving with the piston rod, but of course arranged on the exterior of the cylinder 18. Conveniently the adjustable-throw connection of lever 51 with link 43 may be provided by making the head 50 (Fig. 4) connectible 40 with lever 51 by a non-circular shaft 54, and providing in the head 50 for each of the positions that the head may take with respect to lever 51, a properly positioned hole 55, each a different radial distance from the rotative axis of the head, to receive the crank pin 49. A guide 56 on the upper end of the valve-casting may keep the link 43 always in vertical position, for alignment with valve stem 30 on link 44.
- 45 In operation the piston 17 stands normally between its extremes of movement in the cylinder, maintained against rising under the constant effort of the weight 19 by the presence of a liquid body filling the cylinder 50 above the piston and pocketed in the cyl-

inder by the normal closure of port 20 by the lower head of the valve member 30. This condition will be changed only in response to valve operations initiated by the condition-responsive device 16. Assume 70 boiler pressure to drop: such change should be met by an opening action of the damper tending to increase the draft, and the engine 14 effects such damper-adjustment. The pressure drop in the boiler permits the pressure gauge 35 to contract, exerting a downward pull on link 44 so that the left end of lever 40, fulcruming on pivot point 41, rises, raising the valve 30 to open port 20 in communication with the relief passage 31. 80 Weight 19 now raises the piston, forcing liquid out of the space above it, but as the piston rises it carries with it lever-arm 51, turning crank head 50 and pulling down on link 43, so that the left end of lever 40, now 85 fulcruming on the pivot point 42, is depressed until the valve is again neutralized, that is to say, positioned so that its lower head closes the port 20. Of course the raising of the piston rocks lever 21 to move the 90 damper 13 toward open position. On rise of boiler pressure the engine piston will be depressed against the tension of weight 19, to impart a closing movement to the damper and throttle-down the draft. The rise in 95 boiler pressure expands the gauge 35 so that link 47 lifts the right end of lever 40 and depresses the valve 30 until the space between the valve heads opens connection between pressure supply pipe 27 and the cylinder. Hydraulic pressure forces down the piston, until the stated link and crank connections between the piston rod and lever 40 raise the valve to neutral position.

100 It will be understood that while I have shown details of engine construction in a very simple form having many advantages, and some of the features of which I may claim, for their specific merits, my invention is not limited thereto in its broader aspects 105 and many departures from the precise mechanism shown may be made within the spirit of my invention and within the scope of the appended claims.

110 I claim:

1. In a device of the character described, a cylinder, a single piston therein loaded to tend to move toward one end of said cylinder, liquid-pressure supply and relief connections for said end of said cylinder, valve-means normally closing both of said connections and movable to open either thereof alternatively, a pressure-responsive device having a portion movable under changes of pressure, a valve-moving lever pivotally connected with the movable portion of said valve, a link connection between said lever and the movable portion of said pressure-responsive device, a link (43) also connected with said valve-moving lever, a crank ad- 115

justably and pivotally connected with the other end of said last-mentioned link to shift the latter bodily with throw variable by said adjustment, and an operating connection for said crank movable with the piston to turn said crank, said two links providing alternative fulcrum for said lever whereby operation of said pressure-responsive device, rocking said lever on the other link may open said valve to connect the cylinder with either the pressure or relief connection, and resultant movement of said piston, operating said crank and its connected link will restore the valve to closed position.

2. In a device of the character described, a cylinder, a piston therein loaded to tend to move toward one end of said cylinder, hydraulic pressure supply and relief connections for said cylinder end, valve-means normally closing both said connections and movable to open either thereof alternatively, a Bourdon spring pressure-responsive device, operative connections between said device and the valve means for moving said valve

in either direction, and operative connections including a crank and a link relatively adjustable to vary the effective throw of the crank, arranged between the piston and said valve means for restoring the latter to normal position.

3. In a device of the character described, a cylinder, a piston therein loaded to tend to move toward one end of said cylinder, hydraulic pressure supply and relief connections for said cylinder end, valve-means normally closing both the connections and movable to open either thereof alternatively, a lever connected to said valve, a pressure-responsive device operatively connected to said lever at one point, a link operatively connected with another point of said lever, a crank member, means to connect said crank member and link in different positions of adjustment to vary the effective throw of the crank, and operative connections between the piston and said crank, substantially as and for the purpose described.

CURTIS L. HOWSE.
